Primary Examiner — Kimberly Barnes

(57) **CLAIM**

The ornamental design for a helmet, as shown and described.

DESCRIPTION

FIG. 1 is a top front left isometric view of a helmet showing my new design;

FIG. 2 is a top front right isometric view thereof;

FIG. 3 is a bottom front left isometric view thereof;

FIG. 4 is a bottom front right isometric view thereof;

FIG. 5 is a front view thereof;

FIG. 6 is a rear view thereof;

FIG. 7 is a left view thereof;

FIG. 8 is a right view thereof;

FIG. 9 is a top view thereof; and,

FIG. 10 is a bottom view thereof.

Broken lines in FIGS. 1-10 are for environmental purposes and form no part of the claimed design.

1 Claim, 10 Drawing Sheets
